Des. 220,489
Patented Apr. 20, 1971

220,489

VEHICLE LAMP SOCKET

Takeshige Fujita and Tetsuo Tsuruta, Tokyo, Japan,
assignors to Stanley Electric Co., Ltd., Tokyo, Japan

Filed Dec. 11, 1969, Ser. No. 20,450

Term of patent 14 years

Int. Cl. D13—03

U.S. Cl. D26—1

FIG.1

FIG.2

FIG.3

FIG.4

FIG.5

FIG.6

FIG. 1 is a front elevational view of a vehicle lamp socket showing our new design;

FIG. 2 is a rear elevational view thereof;

FIG. 3 is a top plan view thereof;

FIG. 4 is a side elevational view thereof;

FIG. 5 is a rear perspective view thereof;
FIG. 6 is a front perspective view thereof, the lamp being shown in broken lines for illustrative purposes only.

We claim:

The ornamental design for vehicle lamp socket, substantially as shown and described.
